UNITED STATES PATENT OFFICE.

HARRY V. PADFIELD, OF ST. LOUIS, MISSOURI, ASSIGNOR OF ONE-HALF TO
JOHN W. CORNELIUS, OF SAME PLACE.

DESIGN FOR A NUT-LOCK WASHER.

SPECIFICATION forming part of Design No. 30,153, dated February 7, 1899.

Application filed December 19, 1898. Serial No. 699,780. Term of patent 14 years.

To all whom it may concern:

Be it known that I, HARRY V. PADFIELD, a citizen of the United States, residing in the city of St. Louis, State of Missouri, have invented and produced a new and original Design for a Nut-Lock Washer, of which the following is a specification.

Figure 1 is a plan view, and Fig. 2 is an edge view, as seen looking in the direction indicated by the arrow 2 in Fig. 1.

The leading or essential feature consists of a plate 3, having the central opening 4, having the slit 5 extending from the outer edge

of the plate on a line that will pass and miss the opening 4 and having the slit 6 extending from the slit 5 to the opening 4, the portion 7 of the plate extending downwardly and the free end of the portion 8 being slightly above the body of the plate.

I claim—

The design for a nut-lock washer substantially as herein shown and described.

HARRY V. PADFIELD.
